The ornamental design for a nozzle for plasma arc torch, as shown and described.

DESCRIPTION

FIG. 1 is a bottom perspective view of a nozzle for plasma arc torch showing my new design;

FIG. 2 is a top perspective view;

FIG. 3 is a typical side elevational view;

FIG. 4 is a top plan view;

FIG. 5 is a bottom plan view; and,

FIG. 6 is a cross-sectional view as taken from line 6—6 of FIG. 4.

FIG. 1.FIG. 2.FIG. 3.FIG. 4.FIG. 5.FIG. 6.
